INTERNAL COMBUSTION ENGINE

Edwin Jacobsen, Glendale, Calif.

Application June 17, 1938, Serial No. 214,229

7 Claims. (Cl. 123—197)

My invention relates to improvements in engines and the like in which the connecting rod is hinged intermediate of its ends and having a mechanism acting on the hinged connecting rod for varying the position of the piston relative to the position normally indicated by the position of the crank shaft.

The primary object of the invention is to provide an engine wherein the piston makes predetermined progress in its course of travel while the crank shaft travels at uniform angular velocity.

A further object of the invention is to provide an engine with greater thermo efficiency than heretofore attained.

A further object of the invention is to provide an internal combustion engine that will permit a higher compression ratio to be employed, than generally permissible, without detonation.

A further object of the invention is to provide an internal combustion engine wherein the maximum internal stresses are reduced.

A further object of the invention is to provide an internal combustion engine that will produce a greater horse power per unit weight than heretofore attained.

With these and incidental objects in view, the invention consists in certain novel features of construction and combination of parts, the essential elements of which are set forth in the appended claims, and a preferred form of embodiment of which is hereinafter shown with reference to the drawings which accompany and form a part of this specification.

In the drawings:

Fig. 1 is a side elevation of the engine.

Fig. 2 is an enlarged cross-sectional view taken on line 2—2 Fig. 1.

Fig. 3 and Fig. 3A are diagrams of the positions of the several parts of the engine, plotted for every twenty-two and one-half degrees travel of the crank shaft.

Fig. 4 is a diagram of the piston positions of a conventional engine comparable in size to the one shown in Fig. 2 and the diagram in Fig. 3.

Fig. 5 is a fragmentary top view of the connecting rods showing the bifurcated ends.

The block and base casting 1, its cylinder head 2, the valve cover 3, the gear case cover 4, and the oil pan 5, constitute the main stationary part of the engine. The valve 6, the valve spring 7, the valve keeper 8, the valve lifter 9, and the cam shaft 10 are conventional in design and operation. The piston 11 and the crank shaft 12 are also conventional. The connection be-

tween these two elements is accomplished with the connecting rods 13 and 14, and for this description are referred to as the main connecting rods. The auxiliary connecting rod 15 is freely hinged to the rods 13 and 14 by the common pin 16 and the upper end of the rod 13 is movably secured to the piston by the piston pin 17. The lower end of the connecting rod 14 is journaled to the crank pin 18 and the large end of the auxiliary connecting rod 15 is journaled to the crank pin 19, which is a part of the auxiliary crank shaft 20. Both of the crank shafts turn clockwise as indicated by the arrows and are geared together by the gears 21 to turn in unison, by which term is meant that the two shafts function in exactly the same manner, rotating at the same speed in the same direction. The cam shaft is also geared to the main crank shaft and the above mentioned gears are all enclosed by the gear case cover 4.

As force is applied to the piston it sets the crank shaft 12 in motion and it in turn imparts motion to the auxiliary crank shaft 20. The influence of the latter shaft on the connecting rods 13 and 14 is to either shorten or lengthen the distance between the piston pin 17 and the crank pin 18, and this action gives the piston a progress in its travel not indicated by the position of the crank pin 18. Hence by careful planning it is possible to give the piston a predetermined motion desired to better conform to the burning and expansion characteristics of the fuels used. In the case shown the predetermined progress of the piston was planned to permit the gas to expand more at the extreme upper end of the power stroke to obviate excess loss of heat by conduction, etc., through the cylinder head and walls. Also to arrest undue conversion of pressure into velocity or turbulence that cannot within the combustion chamber be reconverted to pressure. The diagram in Fig. 3 illustrates the predetermined motion of the piston in this particular application showing the relative positions of the crank pins 18 and 19, the pin 16 and the piston. I use the letters in the diagrams to mark the position of these parts at twenty two and one half degree intervals of the crank shaft's travel. The letter *a* designates the piston, crank pins, and the position of the pin 16, as shown in Fig. 2. The piston positions are indicated on the vertical line *a* to *j* on the right side of the line indicating the intervals on the downward stroke, thence returning on the left side *k* to *p* indicating the intervals on the upward stroke. For comparison and to better illustrate the in-

vention the diagram of the piston positions of an engine of comparable size but of conventional design is shown in Fig. 4. It may be seen from the charts that in the first twenty-two and one-half degrees of crank shaft rotation that the piston travel *a* to *b* is much greater in Fig. 3 than in Fig. 4. This condition will permit the use of a higher compression ratio in the former and also reduce the maximum interval stresses which usually occur in this range. By further comparison of the charts it may be seen that not only are the torque characteristics of this engine different, but it also permits the utilization of a greater portion of the available heat. It is interesting to note that in the particular engine shown that the piston is not at bottom dead center until the crank pin 18 reaches the *j* position as noted in the diagram, or twenty-two and one-half degrees past bottom dead center. The character of the piston travel may be varied by varying the timing between the crank shafts 12 and 20, or by changing the position of either of the crank shafts or by varying the link mechanism made up of the three connecting rods 13, 14, and 15. I prefer and show a harmonic link mechanism but good results and even greater latitude is offered by cam, intermittent or quick return motions so well known to the mechanical arts. The action on the piston by any of the above mechanisms can be used to produce desirable results on the induction, compression, expansion and exhaust strokes of the four stroke cycle engine as shown in the drawings. It is obvious that it is just as applicable to the ported or two stroke cycle engines as well as other engines using pressure to move a piston.

While the form of mechanism herein shown and described is admirably adapted to fulfill the objects primarily stated, it is to be understood that it is not intended to confine the invention to the one form of embodiment herein shown and described as it is susceptible of embodiment in various forms all coming within the scope of the claims which follow.

I claim:

1. In an internal combustion engine, a piston, a crankshaft intersected by the piston axis, a connecting rod interconnecting the piston and crankshaft and made in two parts hinged together, an auxiliary crankshaft at one side of the piston axis, a pitman from said auxiliary crankshaft to the hinge of said rod, and means causing the two shafts to rotate at the same speed.

2. The combination with the piston and crankshaft of an internal combustion engine, of a connecting rod directly interconnecting said two parts, said rod having a hinge joint intermediate its ends, an auxiliary crankshaft at one side of said rod, a pitman from the crank of said auxiliary shaft to the hinge joint of the rod, and

means causing the two shafts to rotate at the same speed in the same direction.

3. The combination with an engine piston and crankshaft, of a connecting rod therebetween, and means operatively connected with said rod for imparting increased movement to the piston relative to the crankshaft movement at the beginning of the power stroke, decreased relative piston movement during the center portion of the stroke and gradual increase of movement during the remainder of the power stroke.

4. In combination with the piston and crankshaft of an internal combustion engine, of a connecting rod directly interconnecting said two parts, said rod having a hinge intermediate its ends, an auxiliary crankshaft at one side of said rod, a pitman from the crank of said auxiliary shaft to the hinge joint of the rod, and means causing the two shafts to rotate at the same angular speed.

5. The combination with an engine piston and crankshaft, of a connecting rod therebetween, and means operatively connected with said rod for imparting greatly increased movement to the piston relative to the crankshaft movement during the first twenty-two and one-half degrees of movement of the latter on the power stroke, sharply decreased relative piston movement during the center portion of the stroke and sufficient gradual increase of movement of the piston during the remainder of the power stroke to equalize the power stroke with the intake stroke.

6. The combination with an engine piston and crankshaft substantially aligned therewith, of a composite connecting rod directly interconnecting said parts, and means operatively connected with said rod gradually to modify the relative angular position of its component parts during the piston movement, thereby to cause greatly accelerated speed of the piston during the initial power stroke, greatly decreased piston speed during the center portion of the stroke and gradually increased speed during the remainder of the stroke.

7. In an internal combustion engine having its piston axis intersecting the crankshaft center, a two-part piston rod pivotally joined intermediate its ends, and means operatively connected to the joint of said rod for controlling the angular interrelation of the two piston rod parts during the piston movement thereby to cause greatly increased movement of the piston relative to the crankshaft movement during the initial portion of the power stroke, sharply decreased piston movement during the center portion of the stroke, and sufficient gradual increase of piston movement during the remainder of the power stroke to equalize it with the intake stroke.

EDWIN JACOBSEN.
